(Cl. D34—4)

To all whom it may concern:

Be it known that we, Marion N. La Vielle and Henrietta B. Heller, both citizens of the United States of America, residing at city of Louisville, county of Jefferson, and State of Kentucky, have invented a new, original, and ornamental Design for a Doll, of which the following is a specification, reference being had to the accompanying drawing, forming part thereof.

We claim:

The ornamental design for a doll, as shown.
